ATTORNEYS.

UNITED STATES PATENT OFFICE

ORVILLE C. JOHNSON, OF AURORA, ILLINOIS

CLOSURE FOR BUILDINGS

Application filed October 11, 1930. Serial No. 488,104.

This invention relates to closure operators, and more particularly to that type involving an automatic raising and lowering of a sectional closure upon the application of a weight on an associated part. It has its special application to a garage door where platforms or tracks for a motor vehicle are provided at either side of the door, one end of said platforms or tracks being depressed and 10 the movement translated into a raising movement of the door.

It has for its object the improvement of the details of construction of such a device. A further object is the production in a device of the character described of a neatly fitting closure. A further object of the invention is the simplification of the means for converting a short movement of the platforms into an increased movement in the door.

20 A still further object of the invention is the provision of the door with fittings therefor, adapted to be shipped to a builder and by him inserted in a standard garage door opening.

25 Other objects and advantages of the invention will hereinafter appear in the following description and the novel features thereof will be particularly pointed out in the appended claims.

30 Like reference characters indicate like parts throughout the several figures of the drawings, in which

Fig. 1 is a front elevation looking from the inside of the door, parts being shown as 35 broken away.

Fig. 2 is a vertical sectional view showing the operating parts attached to the jamb.

Figs. 3 to 6 are details.

35 The numeral 10 indicates as a whole the sectional closure, 11 the jambs in which it is mounted, while 12 and 13 indicate, respectively, the outside and inside platforms or tracks, the movement of which operates mechanism which raises the door.

40 The closure shown is made in two sections, 14 and 15, hingedly connected upon their inner faces, the upper section being pivotally mounted between the jambs 11, 11 behind the timber 16 across the top of the jambs, enabling the closure to fit neatly against the face

of the jambs. This upper section, measured from the pintle to the lower edge, is slightly shorter than the lower section, measured from the roller to the upper edge, for the purpose of enabling the maximum of opening without danger of locking the sections in their raised position. This will be illustrated from the dotted line showing of the closure sections in raised position in Fig. 2.

The floor sections are shown in the form of platforms, one within the building and the other outside. The outside platform or track is mounted between suitable copings, not shown, flush with the platform when the closure is down, making a neat and snug fit therewith. The platforms are connected in any suitable manner as at 16', to operate in unison. As shown an angle 13' is mounted on one edge of the platform 13 and one leg of this angle forms a shelf for the support of the contiguous edge of the platform 12.

It will be appreciated that by thus forming the two platforms, their weight together with this simple construction will enable them to operate in unison. It will be further appreciated that the forward edge of the platform 12 lies under the door in its closed position and therefore makes a tight fit.

On each of the jambs is a latch 17 which is provided with a pivoted hook 18 under the tension of a spring 19. At the opposite end of the latch is a sheave 20 over which a power cable 21 takes in the operation of the door.

This power cable is attached at one end to the angle on the platform 13 as shown at 22 and at its other end is secured to a plate 47, attached to the door above and to the rear of a pivot or pintle 41 to be hereinafter described.

It is necessary to confine the movement of the lower section of the door to one which will produce the collapsed or folded condition as illustrated in dotted lines in Fig. 2. To this end each side of the door at its lower end is provided with a roller 29 and on the face of each jamb is provided a track-way 30 consisting of a channel iron in which the roller is confined to a movement in a vertical direction only. It will be appreciated by this construction that the lower end of the door can-

not leave the jamb and that only the abutting portions of the hinged sections will be permitted to a movement away from the jamb.

5 By this construction, when a weight of sufficient magnitude is placed upon either of the platforms 12 or 13, the door is first unlatched by the action of the cable 21 upon the latch 17 and then lifted to open position.

10 In the upward movement of the upper door section the lower door section follows. At first this lower door section is lifted vertically without any overhang, but in the upward movement it extends outwardly and

15 produces considerable overhang which produces a cushioning effect. The result of these features prevents the door from raising with a slam.

It will be understood that the relative 20 weight of automobile to be used with the garage, taken in connection with the weight of the platforms 12 and 13 bears a relation to the weight of the door and the amount of leverage produced, so that in neither the 25 raising nor the lowering of the door will there be an undue slamming.

The door will descend to its closed position and will latch itself. For this purpose latch elements 31 are provided upon the 30 upper portion of the lower section of the door.

In Figs. 3 to 6 are shown the details of the mounting of the upper end of the door. The upper door section is provided on its 35 rear face with a bracing angle 39 and on its edges 38 with an angle 40, both of which are securely fastened to the door section by any suitable means. A pintle 41 is secured in a recess in the door and extends through an 40 aperture in the angle 40. A bolt 43 passes through the angle 40, an aperture in the pintle 41, a portion of the door 38, and through the angle 39, and thus securely holds the pintle in place in conjunction with the 45 aperture in the edge portion of the angle 40.

The upper end of the jamb is also recessed as at 44 for the purpose of receiving the bearing plate 45 which consists of a base and a bearing socket 46. It will be appreciated 50 that both sides of the jamb are thus provided with sockets for the reception of the pintles of the door and that to remove the door from these sockets it is only necessary to elevate it slightly so that the pintles will pass 55 clear of the upper edges of the socket.

The upper end of the angle 40 is provided with a plate or heel 47 in which is an aperture 48. By means of this aperture the cable 21 may be attached to the heel 47.

60 What is claimed is:

1. In a door and operator combination designed for insertion in a standard garage door opening, a door comprising hinged sections, means for pivotally mounting the upper section and for slidably holding the

lower section between the jambs of the door opening, an extension of the upper section providing a point of attachment for an operating cable above and behind the pivots of the door, and means for opening the door comprising an operating cable connected to said door extension and lying behind the door.

2. The combination of claim 1 in which compressible platforms are employed as prime movers of the operating means, to which platforms the cable is attached.

In testimony whereof I affix my signature.

ORVILLE C. JOHNSON.
